United States Patent Office

Des. 178,783

Patented Sept. 18, 1956

178,783

COMBINED BOOKCASE AND COFFEE TABLE

Richard King, Jackson, Miss., assignor to Sears, Roebuck and Co., Chicago, Ill., a corporation of New York

Application December 8, 1955, Serial No. 39,219

Term of patent 14 years

(Cl. D33—14)

Fig.1.

Fig.2.

Fig. 1 is a perspective view of a combined bookcase and coffee table embodying my design, and

Fig. 2 is an end elevation of the same.

The side and end of the article opposite the side and end shown are the same in appearance, respectively, as the side and end illustrated.

I claim:

The ornamental design for a combined bookcase and coffee table, as shown and described.
